DESIGN FOR A HANDKERCHIEF

Solomon E. Rains, New York, N. Y.

Application July 15, 1936, Serial No. 63,842

Term of patent 3½ years

To all whom it may concern:

Be it known that I, Solomon E. Rains, a citizen of the United States, residing at Manhattan, in the county of New York and State of New York, have invented a new, original, and ornamental Design for a Handkerchief, of which the following is a specification, reference being had to the accompanying drawing, forming part thereof.

The single figure is a plan view of the corner

of a woven textile fabric handkerchief body, parts being broken away, showing the design in embroidery with color indicated as per the color chart of the rules of practice. The other parts of the handkerchief are shown unornamented.

I claim:

The ornamental design for a handkerchief as shown and described.

SOLOMON E. RAINS.
